UNITED STATES PATENT OFFICE

ANDREW M. RITCHIEY, OF SAN ANTONIO, TEXAS

TRAIN ORDER SIGNAL

Application filed February 16, 1931. Serial No. 516,234.

The invention relates to train order signals, and has for its object to provide, in connection with pivoted signal arms adapted to be placed in stop or clear position for trains going in either direction, cabinets in which train orders are disposed and the cabinets with doors positioned whereby they can not be opened, except when the signalling arms are in the stop position, and at which time 10 the operator may have access to the orders for making out the orders and delivery to the train crew.

A further object is to provide boards having clips for the reception of train orders, 15 which boards are received within the cabinets on shelves. Also to provide the boards of each cabinet with notches adapted to receive flanges within the cabinets whereby the boards of one cabinet can not become mixed 20 with the boards of the other, thereby providing positive means for preventing the mixing of north and south order blanks.

A further object is to provide hinged strips at the forward edges of the shelves within the 25 cabinet, and which strips, when the order boards are moved from the shelves, hinge outwardly, and assume positions where they hold the cabinet doors in right angle open positions in the path of arms carried by the operating mechanism for preventing movement of 30 the signalling arm to clear position until the train order board has been placed in either cabinet.

A further object is to place the door engaging 35 arm in operating mechanism, spaced above the door of the cabinet a sufficient distance to allow the signalling arm to be oscillated slightly on its stop position for indicating to the crew of an approaching train 40 to slow up for the reception of the usual stop orders, but at the same time not far enough from the door to allow the signalling arm to assume the clear position until the door is closed.

A further object is to pivotally connect 45 levers to the sides of the cabinets, and to provide the levers with arms connected to the signalling arm mechanism, and with angularly shaped arms overlying the adjacent sides of the cabinet in the path of the doors

when the doors are open. Also to provide downwardly extending operating rods pivoted to the levers within reach of the operator, and means adjacent the operator's position for holding the rods against movement 55 in one direction until released.

With the above and other objects in view the invention resides in the combination and arrangement of parts as hereinafter set forth, shown in the drawings, described and 60 claimed, it being understood that changes in the precise embodiment of the invention may be made within the scope of what is claimed without departing from the spirit of the invention. 65

In the drawings:

Figure 1 is a view in elevation of a portion of a railroad station or other building showing a portion of the operator's desk and the train order signalling device in elevation. 70

Figure 2 is a perspective view of one of the train order cabinets, showing the door open.

Figure 3 is a perspective view of the cabinet, showing the door closed, and the door-holding mechanism in operative position. 75

Figure 4 is a perspective view of one of the train order boards.

Figure 5 is a horizontal sectional view through one of the cabinets showing the door open. 80

Figure 6 is a vertical transverse sectional view through one of the cabinets.

Figure 7 is a perspective view of another train order board.

Referring to the drawings, the numeral 1 85 designates the operator's desk within the station 2, and disposed on the wall 3, preferably adjacent the window 4 thereof are the train order cabinets 4 and 5. Cabinets 4 and 5 are of the same construction and operation, and all the mechanism connected thereto, with the exception of a minor nature, hereinafter specifically pointed out, therefore the same numerals will apply thereto. The mechanisms are duplicated for independently controlling traffic in two directions. 90

Each cabinet comprises a body member 6 and a hinged cover 7, hinged to the body member at 8. Pivotally connected at 9 to the side of the body 6 is an outwardly extending 100

lever 10, to the outer end of which is connected a downwardly extending rod 11, which terminates in a loop 12, adapted to be grasped by the operator for imparting a 5 downward swinging movement to the lever 10 until the loop 12 is in a position to be received on the hook 13 adjacent the operator's desk 1.

Extending upwardly and inwardly from the upper side of the lever 10 is a door limiting arm 14, which when in down position as 10 shown in Figure 3, with the door 7 in closed position, will prevent the door from being opened, and at which time the signalling arm 14 is in clear position vertically, as shown in 15 Figure 1. When the signalling arm is in clear position, the operator can not open the cabinet door for removing the train order board 15 therefrom. When the lever 10 is in raised 20 position as shown to the left of Figure 1, and also in Figure 2, the signalling arm is in horizontal stop position, and the door holding arm 14 is in a position above the door, and at which time the operator may open 25 the door and remove the train order board 15 therefrom, which normally rests on the shelf 16. As the train order board 16 is removed from the cabinet, the operator swings outwardly the pivoted strip 17 which assumes a horizontal position and prevents the 30 door 7 from closing, and at the same time holds the door in the path of the the limiting arm 14, thereby preventing extreme downward swinging of the operating arm 10, consequently prevents the signalling arm from 35 being swung upwardly to clear position until after the train order board has been placed in the cabinet and member 17 hinged upwardly.

Lever 10 is provided with an upwardly extending arm 18, to which is connected an upwardly extending rod 19, which may extend to a signalling post or other structure, and is pivoted at 20 to a bell crank lever 21, which bell crank lever is connected by means of a 40 rod 22 to a second bell crank lever 23, having a rod connection 24 with the pivoted signalling arm 14, therefore it will be seen that through this rod and leverage connection, the operator may positively control the swinging 45 movement of the signalling arm 14. It is obvious that this leverage connection will vary according to the type of signalling post or other structural details.

By referring to Figures 1 and 2, it will 50 be noted that the arms 14 which overlie the cabinets in the path of the doors 7 when opened, are spaced above the doors and cabinets a sufficient distance to allow the operator to oscillate the signalling arms as a signal 55 to approaching train crews to slow down sufficiently to receive a train order manually passed on the usual train order hoop. Most standard railroads use a form of train order known as the number 19 train order form, 60 which allows the delivery of a train order by

the operator without stopping the train. In operation, the operator indicates to the train crew the desire to deliver a train order by clearing the blades of train order signal arms twice and returning signal to stop, and 70 leaving the signal in stop position until train has passed and orders delivered. In the present device the train order signal is pulled down from clear position a limited distance with the cabinet door open for the signalling 75 operation; however the signal must be placed in stop position before operator can get train order blanks to copy the train order.

The operator, however, can not obtain his 80 blanks until instructed to do so by the train dispatcher, and after instructions from the train dispatcher the signalling arm can not be placed in clear position until operator's table is cleared of orders. There are certain 85 rules which will have to be imposed on the operator to be observed in connection with the device. The train order operator must be required to keep his train order blanks in cabinets and the cabinets closed. When orders are put out at his office, he will copy 90 the same on the proper form, taken from the cabinet; when orders are received and copied and made complete he will remove the required copies from manifold for delivery to 95 trains and hoop these copies. The operator must leave his office copy on manifold and clip until orders on hoops have been delivered to the proper trains, to whom addressed. He will then return to his office, 100 report to train dispatcher such action completed and ask dispatcher to clear his table of such orders or all orders, as the case may be. When so cleared he will remove his copy from manifold and clip and return clip board to the cabinet, close cabinet, and if all orders are cleared 105 from table will then clear signal or leave signal at "stop" as the case may be, as required by the rules. All train order blanks must be kept on the boards provided for them and in the cabinets, as shown in the drawings. It 110 will be noted that the clip board 15 has its edge provided with two notches 15a which receive the vertical strips 25 when the clip board is placed in the cabinet. It will be noted by referring to the clip board 15b that 115 a single notch 15a is shown, which receives the single strip 15c in the other box, and as said clip boards are proportioned to substantially fill the box with the exception of the hinged strip width 17, said boards can only 120 be received in their proper boxes, hence train orders for north and south traffic will not become mixed.

The invention having been set forth what 125 is claimed as new and useful is:—

1. The combination with a vertically and longitudinally movable operating arm for a pivoted signal arm, of a train order cabinet adjacent the end of said arm, a lever pivoted 130 to the side of the cabinet, a depending rod

connected to said lever, a hinged closure carried by the cabinet, an arm carried by the lever and extending inwardly and overlying the cabinet, said last named arm being positioned whereby when the lever is in down position the closure of the cabinet will be prevented from being opened.

2. The combination with a train order cabinet, a signalling arm operating rod, of a lever pivoted to the cabinet, said rod being pivoted to the lever at a point spaced from its pivotal point, means for forcing said lever downwardly in relation to the cabinet, a hinged closure carried by the cabinet and an arm carried by the lever and overlying the cabinet and positioned whereby when the lever is in raised position the cabinet may be opened and when the lever is in lowered position the cabinet closure is held against opening.

3. The combination with a train order cabinet, a signalling device, means for controlling the signalling device, a hinged closure carried by the cabinet, means for holding said closure against opening when the signal is in a certain position, a hinged strip within the cabinet and adapted to hinge outwardly into the path of the closure and hold the same against closing until a train order board has been returned to the cabinet and means whereby only the proper board can be placed within the cabinet.

4. The combination with a movable operating arm for a signalling device, of a train order cabinet adjacent the end of said arm, a lever pivoted adjacent the cabinet, a hinged closure carried by the cabinet, an arm carried by the lever and extending into the path of the hinged closure whereby when the lever is in one position the closure of the cabinet will be prevented from being opened.

5. The combination with a train order cabinet, a signal arm operating member, of a lever pivoted adjacent the cabinet, said signal arm operating member being pivoted to the lever at a point spaced from its pivotal point, means for moving said lever in relation to the cabinet, a movable closure carried by the cabinet and a member carried by the lever and overlying the cabinet and positioned whereby when the lever is in one position, the cabinet closure may be opened and when the lever is in another position the cabinet closure is held against opening.

55 In testimony whereof he hereunto affixes his signature.

ANDREW M. RITCHHEY.
